MECHANICAL PENCIL WITH STEP-BY-STEP PUSH FEED

Edwin C. Hedler, Chicago, Ill.

Application February 7, 1946, Serial No. 646,104

12 Claims. (Cl. 120—17)

1

This invention relates to an improved and positive type mechanical writing device particularly adapted to so called lead or graphitic writing devices or pencils but obviously having other uses and extensions within the knowledge and skill of one working in this art. More specifically it relates to a magazine type of an automatic pencil that is adapted to hold a plurality of leads and which positively dispenses each lead individually of a proper and suitable length for writing without breakage, jamming or other difficulties inherent in the present type mechanical pencils of the step-by-step or push feed type.

It therefore is an object of this invention to provide an efficient mechanism having few parts and economical to produce. It is further characterized by its ease of assembly and ability to utilize even small leads that may be inadvertently broken in the magazine.

These and other objects, adaptations, uses, modifications and variations will be readily apparent to one skilled in this art particularly in view of the lucid, definite and detailed description of the mechanism, the parts thereof and the fundamental elements underlying the principles involved in this invention as given hereinbelow and illustrated in the attached drawings forming a part hereof.

In the drawings,

Figure 1 shows an axial elevation of the pencil partly broken away.

Figure 2 is a somewhat similar but partly broken away elevation showing the lead clutch opening means in greater detail.

Figure 3 shows an elevation somewhat similar as Figure 2 but showing the clutch in full engagement.

Figure 4 shows in an enlarged detail the lead gripping or clutch means in an open position.

Figure 5 is a section enlarged showing the lead alignment tube details and its relationship to the tip.

Figure 6 is a plan view of the clutch jaws in a closed position. Figure 7 is a similar view wherein the jaws are shut about a lead while Figure 8 shows a similar view to Figure 7 but with the jaws in the open position.

Figure 9 is a sectional view of a modification of the clutch device or means while Figure 10 is an end view of the clutch jaws taken along lines 10—10 of Figure 9.

Essentially the pencil consists of an outer barrel or pencil case proper, 10, made of plastic, metal or some other suitable and desirable material. The barrel 10, ends in a tip 12, thru

5 which the pencil lead 20, protrudes when in a writing position. The tip 12, is preferably of metal and contains therein a number of slots to form spring-like segments 14 to grip the lead and prevent it from rotating about when the pencil is used. These segments 14 (all not shown in Figure 1) form a bore about the lead 20. Within the bore and at the upper part of segments 14, is an annular shoulder or collar 16, 10 which is an integral part of the segments. The floor of this shoulder slopes downwardly to provide a slide for the lead 20, as it moves forward under the urging of the propulsion unit shown in detail in other figures. Furthermore, it provides 15 space for the segments 14 to operate in for they have induced spring characteristics which grip the lead 20.

The guiding and gripping portion 16 of the tip is press fitted or molded into place in the 20 tip 12. The tip 12 may be made from the same material as the barrel or case proper 10, or if it is desired may be made from another. The tip 12, by means of a male thread, 18, fits into the internal thread on the lower part of the tube body 10, and thus completes the lower outside 25 surface of the pencil.

In the upper part of the tip 12, and substantially coaxially located within the perimeter bounded by the threads 18, is an annular chamber 22. The 30 upper part of the chamber 22 is threaded with threads 24, which receive the threads 26. The latter are an integral part of the collared guide sleeve 28. However, both threads may be omitted and the sleeve 28 may move freely in the chamber 22. This sleeve 28, is press fitted within the walls of the retainer tube 30, which also houses the co-operating gripping or clutching mechanism and related elements. The annular chamber 22 has the lower portion thereof free of threads so 35 that the clutch mechanism stripping tube head or rim 32, can move smoothly and freely within it thru a predetermined distance. This movement and the amount of distance of travel is important for it controls the distance that the lead will travel while it is being propelled forwardly by the clutch.

Within the upper end of the barrel tube 10, there is concentrically mounted an actuating or push tube 40. Push tube 40 has on its upper end a frictionally engageable button 34. Attached to the said button 34 is an eraser 36, made of rubber, factice and the like, snugly fitted within the bore of the push tube 40. Reserve leads or extras 20 are disposed about in the magazine chamber 38. Magazine chamber 38 has a sloping floor 42,

which centers and guides the lead 20 to a centrally located orifice 44 within the expander or wedge means 46. Both the sloping floor 42 and the orifice or opening 44 are an integral part of the expander means 46.

In order to obtain a more perfect alignment of the entire mechanism, the expander means 46 has an outwardly projecting shoulder or rim 48. It is desirable but not essential that this shoulder be mounted about the midpoint since it was found that the greatest stability in action is obtained at this position. The base of the actuating tube 40 is seated on a part of the said projecting rim 48 while the balance of it is occupied to function as a restraining shoulder on the abutment 50 formed by stepping at the desired position the interior of the body barrel 10.

The lower portion of the expander body 46, is provided with a stepped shoulder 52, which rests on an annular pressure guide sleeve or washer 54. This guide 54, in turn rests on the spring 56. The lower end of the spring in turn rests on the collared guide sleeve 28. A tube 30, is press fitted over or otherwise firmly secured to the collared guide sleeve 28. The upper edges of the tube 30 are preferably turned inwardly to form a retaining shoulder over the guide sleeve 54. This tube 30 retains in place the spring 56, which forces apart the key wedge 58 and the wedge retaining wall 62. The key wedge 58 is preferably an integral part of the expander body 46.

The lower part of the expander means 46 terminates in a particular type of a tapered wedge or key 58. This key is so constructed as to the degree or angle of its taper that it frictionally engages the interior of the wedge retaining walls 62 of the gripping members 64 that are operating on the leads 20.

This angle or degree of taper is the acute angle included by the sloping walls of the key and an imaginary vertex located on an imaginary vertical line extended perpendicularly and coaxially thru the tube or barrel 10 of the pencil. It was found that this wedge must have an angle as defined above within the limits between two and forty degrees. For most practical results it is preferred to use an angle in the range between four and six degrees.

Though it is preferred to use a wedge having a frusto-conical section, it is obvious that the shape may vary over a wide range and still be within the spirit of this invention. For instance, the wedge may be a polygon having an elliptical, triangular, quadrilateral, pentagonal etc., configuration. It is preferred but not essential that the wedge retaining walls 62, have the same degree of angularity and configuration as the wedge key 58 so as to provide the most effective angle of contact between the frictionally engageable surfaces of the expander 46 and gripping members 64. However, it is apparent that any type of an opening in the chamber formed within the periphery of the wedge retaining walls 62, may be utilized provided the wedge key 58 can be inserted therein and is frictionally engaged by the said walls 62. Further, this angle will also vary with the nature of materials used in the making of the mechanism, since the coefficient of friction of such materials will be considered in the design.

But regardless of the shape, the wedge key 58 must perform two functions; (1) it must open the jaws 64 of the clutch body 66 by pressing open the interior walls 62 thereof; and (2), it must be frictionally engageable with the said walls 62. Thus in actual operation the entire clutch body 66 fric-

tionally engaged by and suspended from the wedge key 58 is carried upwardly in an open position by the expanding movement of the compressed spring 56 until the stripper collar 32 on the clutch body 66 prevents further upward travel upon contact with shoulder 68. When this occurs the frictional bond between the wedge key 58 and the walls 62 is broken. The jaws 64 activated by the inherent inward spring tension induced in said jaws clamp or grip the lead 20 and thus remain ready in the position to repeat the feeding of the lead 20 to the tip 12 according to the operation described hereinbelow.

The clutch body 66 consists of a tubular member of a specific design and interior configuration. Though for economical and practical reasons, a cylindrical tubular member is desired, it is obvious that this shape may vary considerably and still be within the fundamentals of the principles as expressed by this invention. For instance, the clutch body member 66 may be triangular, quadrilateral, etc., or if desired any other shaped polygon capable of performing this function and capable of imparting a gripping action on the lead 20. As mentioned above the key or wedge 58 on the expander means 46 should preferably but not necessarily have the same contour as the tapered portion of the restraining faces 62 of the tubular member 66 so that the degree of frictional engagement is of sufficient magnitude to insure proper function. Obviously, under these considerations it is desirable that the contour of both the wedge key 58 as well as the restraining faces 62, be substantially similar, particularly when in full engagement. This frictional engagement obviously can be varied and when properly designed the actual force of this frictional engagement depends largely upon the amount of inherent inwardly inclined spring tension within the jaws. This tension may be modified readily by changes in the dimensions and contour of the clutch body 66.

At the lower end of the lower guide sleeve 28 held in the tube 30, is located a stripping means or shoulder 68. This shoulder 68 upon contact by the upwardly moving rim 32, causes disengagement of the frictionally engaged faces 62 from the wedge 58. This act permits the spring tensioned jaws 64 to close about and grip the lead 20.

The upper end of the clutch body 66 is slotted into one or more segments 70. Each segment 70 has an inner sloping wall 62 which as mentioned above preferably has the same contour as the adjacent complementary face of the wedge 58. The surface of the inner wall 62 terminates as a stop shoulder or lip 74. This lip 74 restrains further entry movement of the key 58.

The lip or stop collar 74 preferably but not necessarily forms the upper part or head of the jaws 64. These jaws 64 are so designed that a portion of the lead 20 is seized and gripped strongly therebetween when they are closed. The clutch body 66 is tubular and preferably formed from spring steel. Slots 72 are cut therein to form a number of segments 70. These are formed in the untempered steel. Prior to the tempering process, they are squeezed together and tempered in that position so that the spring characteristics are induced and developed in the jaws 64.

Within the bore of the clutch body 66 and below jaws 64 is a long narrow alignment tube 78 having an inner diameter slightly larger than the thickness of the lead 20 in its lower portion. The upper part 80 of the alignment tube 78 is

slotted and slightly flared having one or more spring-like segments to retain the lead 20. The diameter of the bore of the alignment tube slightly below the flared portion 80 is slightly constricted to provide a means for gripping the lead by the spring tension provided within the segment walls. This particular feature prevents the accidental retraction of the lead, 20, when the jaws 64 should perchance become fouled with the wax coating scraped from the leads. The alignment tube 78 begins at a point in the hollow chamber below the jaws 64 and terminates above the slot 14 in the tip 12. This tube 78 retains the leads 20 or short sections thereof in perfect alignment so that they are not crushed or crumpled, thereby clogging and jamming the flow of lead 20 at any point of movement.

The operation of this pencil and the function of each part and its relationship to the other elements thereof will now be described.

The lead 20 lying in the magazine chamber 38 guided by the sloping floor 42 of the magazine chamber falls under the influence of gravity into the centrally located orifice 44. The orifice has a slightly larger diameter than the lead 20 which under the influence of gravity drops thru the expander means body 46, into the wedge entry chamber formed by the walls 62. Here it comes to a stop on the wedge stop shoulder 74 of the clutch body 66 since the jaws 64 normally are closed. The inbuilt spring tension of the jaws 64 keeps these closed until they are opened so that the leads 20 can drop further under the action of gravity. The constricted portion of the alignment tube 78 prevents further drop of the leads 20 unless some positive force is used to drive them thru this constriction. Since this alignment tube is just below the jaws 64, it is obvious that even short pieces of lead 20 will be properly fed and held in alignment.

The application of pressure to the button 34, simultaneously transmits it thru the actuator tube 40 which slides concentrically within the pencil barrel or tube 10. The actuator tube 40 is press fitted over the expander means body 46 and rests on the expander body collar 48. The applied pressure is then transmitted onto the collar 48 and to the taper wedge or key 58 which slides within the rolled edge of the retainer tube 30. Within the retainer tube 30 is a guide sleeve and pressure transmitting washer 54. A shoulder 52 preferably an integral part of the expander means body 46 rests on the combination guide and washer 54. As the pressure is applied to the expander means body 46, it in turns bears down on the washer 54 which compresses the spring member 56. The spring member 56 at its lower terminus presses against the guide sleeve 28, which is screwed into or is slip fitted in the tip 12.

At the lower terminus of the expander means body 46 is a wedge or key 58, having a slight taper of the type described above. This key 58 is suspended freely in the chamber bounded by the wedge key restraining walls 62. These as mentioned previously are preferably of the same contour as the complementary surfaces of the wedge 58. As further pressure is applied, the key 58 slidably moves downwardly into the chamber to contact the walls 62 and engage them in a frictional bond as shown in Figures 2 and 3. As still further pressure is applied the key 58 continues to move downwardly carrying with it the walls 62 and the clutch means body 66 of which the

jaws 64 are an integral part. As this downward movement continues eventually the rim 32 contacts the bottom of the chamber 22 in the tip 12.

This contact stops further downward movement of the clutch means body 66 while the penetration of the wedge key 58 continues between the faces 62 of the jaws 64. The latter upon further penetration of the key 58 are pried apart to permit the lead 20 to drop thru into the alignment tube 78, which is nestled within the clutch means body bore. Since the top of the alignment tube 78 is flared and then slightly constricted at 80 to provide a lead holding spring tension, the freely falling lead 20 will come to rest at this point. In the meanwhile further downward movement of the wedge key 58 is prevented by the stop shoulders 74 on the top of the jaws 64. This concludes the downward movement of the entire assembly.

Upon release of the pressure exerted on the pencil top 36 the compressed spring 56 is released and snaps to return the entire assembly to its original position. However further upward movement of the clutch means body 66 is prevented by the bottom rim collar 32 which impinges on the clutch means body stripping shoulder 68. The wedge key 58, in the meantime, moves upwardly until stopped by the shoulder 50. The lead 20 being free of the jaw grip remains in the rest position. As soon as the clutch body 66 is stripped from the wedge key 58 the jaws 64 close tightly about another portion or another coaxial section of lead 20 and thus it is in position awaiting further downward action by the wedge key 58. When this occurs, the lead 20 held by the jaws 64 is again pushed downwardly until the clutch means body rim 32 reaches the chamber 22 floor and again the jaws 64 are pried apart to leave the lead 20 free. This action is repeated until the proper amount of lead is projected thru the friction segments of the pencil tip 12.

As mentioned previously, it is possible to have a number of variations of the clutch means and the components entering into its combination. For instance, Figure 9 shows another variation that can be readily made to serve this purpose. Figure 10 is a section taken along line 10-10 of Figure 9, thru the clutch jaws portion. Essentially it consists of a barrel body 66 having at one extremity the stripping shoulder 32 whose function was previously described. On the outer surface of the body 66 and about the proximity the clutch jaw area is an encircling spring band or split washer 84 riding in a groove 82. This washer holds under its spring tension the segments 70 of the body together so that the jaws of the clutch are in a closed position. The preferred type is the one shown and consisting of a split spring washer or tube type. This type can readily be slipped over the ends of the clutch body and also provides an easy means for removal. The clutch body as shown consists of a barrel having two or more slots cut into one end thereof to provide a series of segments. The jaws on the slotted segments which hold the leads 20 are prevented from opening by the restraining spring washer 84. However, when the wedge key 58 is forced between the surfaces 62, the spring washer 84 and the jaws 64 are spread apart and the lead is free to move. When the wedge is removed, the jaws close.

While it is obvious to one skilled in this art that many modifications, variations, extensions and adaptations are entirely possible, these nevertheless are considered within the scope and spirit

of the fundamental principles underlying this invention as defined by the hereunto appended claims.

I claim:

1. A mechanical pencil of the step-by-step type comprising a barrel, a pointed tip on one end of said barrel, the said tip having therein a bore to receive leads, segments in pointed end of said tip formed by slotting the end of said tip, the said segments having inwardly induced resiliency to form a bore within said end of slightly smaller diameter than diameter of upper lead bore to provide a means to retard exit of the leads, means to attach said tip to the said barrel, a chamber above the said means for retarding exit of leads through the tip, a lead gripping means mounted in said chamber, the said lead gripping means comprising a segmented tube, the uppermost portion of the inner walls thereof tapering inwardly and downwardly to form a conical hollow having an included angle of not more than forty degrees, lead gripping jaws below said hollow, a collar on the lower end of said tube in slidable contact with the walls of said chamber, a detent to engage said collar and to limit the upward travel of said lead gripping means, an engaging and opening means comprising a tapered key having a taper substantially coincidental with the taper of said conical hollow in uppermost part of the segmented tube, a spring means to disengage said engaging means, a means to actuate the said engaging and opening means, and a lead passage through said engaging and opening means in coaxial juxtaposition with lead passage of the lead gripping means and of said tip.

2. In the pencil of claim 1, a lead-aligning tube extending from approximately the lower end of the said lead gripping jaws to approximately the segmented portion of end of said tip.

3. The pencil of claim 2, wherein the said lead-aligning means consists of an elongated tube having throughout its major portion a bore slightly larger than the diameter of the leads, the upper part of said aligning means having a flared, slotted segmented lead receiving cup; the section immediately below and adjacent said flared slotted receiving cup having a constriction therein formed by the converging segments in the upper part of the alignment tube, the said constriction having a diameter slightly less than the diameter of said leads, a spring means inbuilt into said segments of tube to provide a frictional gripping action on the leads, and the lowermost end of said aligning means terminating substantially near the said means for retarding exit of the leads.

4. The pencil of claim 1, wherein the base of said spring actuating means comprises a means for guiding leads to a centrally located bore, the floor of said means for guiding leads sloping downwardly to the said centrally located bore, the said bore extending axially through the said means to engage and open the said lead gripping jaws.

5. The pencil of claim 1, wherein the said means to engage and open the lead gripping jaws terminates in close coaxial juxtaposition to the said lead gripping jaws, the outer walls of the terminus of said jaw-opening means having substantially the same degree of taper as the said inner tapered surfaces forming the conical hollow in the segmented tube above the lead gripping jaws, whereby the said surfaces can be engaged frictionally on substantial contact with each other.

6. The pencil of claim 1, wherein the said lead gripping means comprises a tube-like element, the lower end of said tube-like element having thereon a detent, a means forming a part of said tip assembly to stop further upward movement of said detent on the tube-like element whereby the movement of said lead gripping means is confined to a preselected distance, the upper part of said tube-like element having segments therein formed by slots cut into said tube-like element, each of said segments characterized by inwardly inclined spring force of sufficient strength to retain leads therebetween and resist writing pressure on the leads, the uppermost portion of the interior wall surface of each of the said segments formed to define a tapered hollow in the tube-like element, the said hollow being substantially the same in contour as the related portion of the means to engage and open said lead gripping jaws.

7. The pencil of claim 6, wherein the said means to prevent further upward movement of the lead gripping means comprises a guide sleeve slidably mounted in chamber above the said means to retard exit of leads, the said guide sleeve having a bore sufficiently large to receive therethrough upper portion of said tube-like element, a flange on exterior of said guide sleeve to receive thereon the said spring means, and to prevent downward movement of said guide sleeve.

8. A sub-assembly for the pencil of claim 7, comprising a tube, a coil spring inserted therein, upper end of said tube turned inwardly to provide a retaining shoulder for said coil spring, the lower end of said spring-like coil resting on a guide sleeve, the upper end of said guide sleeve retained slidably within the said tube, and the lower end of said tube turned inwardly to retain the slidable portion of said guide sleeve.

9. In the sub-assembly of claim 8, a means within the upper part of said tube for coaxial alignment of said engagement and opening means with the said lead gripping means.

10. The pencil of claim 1, wherein the said barrel has an annular shoulder and the engaging and opening means have an annular collar thereon to butt against each other when the said engaging and opening means are forced apart by said spring means from said lead gripping means, and to restrain further upward action of said spring.

11. The pencil of claim 1, wherein the said conical hollow has preferably an included angle from four to six degrees.

12. The pencil of claim 1, wherein the said lead gripping means comprises an elongated tube-like element, the upper part thereof having not less than two opposing slots cut therein to form segments, a means on exterior of said slotted portion to exert compressive and resilient pressure on said segmented wall sections and a means to retain said compressively acting means substantially about the desired position.
